D. T. WARREN,
AUTOMATIC STOCK GUARD,
APPLICATION FILED APR. 11, 1917.

1,287,533.

Patented Dec. 10, 1918.

UNITED STATES PATENT OFFICE.

DANIEL THOMAS WARREN, OF MARIETTA, OKLAHOMA.

AUTOMATIC STOCK-GUARD.

1,287,533.

Specification of Letters Patent. Patented Dec. 10, 1918.

Application filed April 11, 1917. Serial No. 161,261.

To all whom it may concern:

Be it known that I, DANIEL T. WARREN, a citizen of the United States, residing at Marietta, in the county of Love and State 5 of Oklahoma, have invented a new and useful Automatic Stock-Guard, of which the following is a specification.

The present invention appertains to cattle or stock guards for railroad tracks, and aims 10 to provide a device of that character of novel and improved construction, whereby the same is effective for preventing cattle or other stock from escaping from an inclosure along the track.

15 It is also the object of the invention to provide a stock guard of simple and inexpensive construction, which can be readily installed upon the track.

With the foregoing and other objects in 20 view which will appear as the description proceeds, the invention resides in the combination and arrangement of parts and in the details of construction hereinafter described and claimed, it being understood that 25 changes in the precise embodiment of the invention herein disclosed, can be made within the scope of what is claimed, without departing from the spirit of the invention.

The invention is illustrated in the accompanying drawing, wherein:

Figure 1 is a plan view of the guard applied to the track.

Fig. 2 is a cross section thereof.

Fig. 3 is a sectional detail taken on the 35 line 3—3 of Fig. 2.

Fig. 4 is an enlarged sectional detail illustrating the means for fastening one of the guard spurs in place.

The numerals 1 designate the rails of 40 the track which are supported by the cross ties 2 as usual.

The present guard embodies transverse bars 3 disposed between the ties and having their ends projecting underneath and beyond the rails 1, there being a series of these 45 bars 3 to effectively prevent the cattle or other stock from passing over the track at this point. As a convenient and desirable manner of supporting the bars 3, longitudinal beams 4 are seated upon the ties 2 at the 50 inner sides of the rails, and the ends of said beams are secured by bolts 5 or otherwise to the corresponding ties 2, to hold the beams in place. The bars 3 are of reduced circular 55 cross section, as at 6, below the beams 4 and rails 1, and U-shaped bearings or seats 7

have their end portions secured to the lower surfaces of the beams 4, and the reduced circular portions 6 of the bars 3 are seated and journaled in the bearings 7. Thus, the 60 beams 4 support all of the bars 3, and said bars can rock about their axes.

A set of upstanding spurs 8 is carried by each bar 3 longitudinally thereof, said spurs being flat and disposed in the vertical plane 65 of the axis of the bar and the upper ends of the spurs being pointed. The spurs are located at the inner and outer sides of the rails, and have reduced shanks 9 inserted downwardly in apertures in the bars 3. 70 Wedges 10 are driven into the lower ends of the shanks 9 to spread them and thereby lock the shanks in their apertures.

Each bar 3 is weighted in order to hold the spurs 8 in a vertical position, and for this 75 purpose, the bar is provided between its ends with a depending staple or loop 11 with which a link 12 is engaged loosely. The lower end of said link is engaged with an upstanding staple or loop 13 provided at 80 the upper end of a weight 14 disposed below the bar and suspended therefrom by the link 12. The weight will therefore pull the loop 11 downwardly to hold the spurs 8 in vertical position, and said spurs can rock 85 with the bar 3 in either direction. Due to the loose connection of the weight with the bar, the weight has but a limited movement between the ties 2, thereby enabling the bar or guard member to rock a considerable 90 amount, which would not be possible if the weight were fixed to the bar so as to have a relatively long arc of movement.

Disposed at opposite sides of the track are sheet metal barriers 15 to prevent the 95 stock from passing along the opposite sides of the track without passing over the spurs 8, which spurs will serve to turn the stock back into the inclosure.

Having thus described the invention, what 100 is claimed as new is:

In a device of the class described, cross ties; track rails thereon; longitudinal beams between the rails and in contact with the inner edges of the rails; means for securing 105 the beams to the ties; bearings on the lower edges of the beams; a bar comprising enlarged ends disposed on the outside of the rails, an enlarged central portion disposed between the beams and engaged at its ends 110 with the beams to prevent the bar from shifting endwise, and circular parts con-

necting the ends with the central portion, the circular parts being journaled in the bearings and extending outwardly beneath the rails; a weight pivotally assembled with
5 the central portion of the bar; and upstanding spurs carried by the ends of the bar and by the central portion of the bar.

In testimony that I claim the foregoing as my own, I have hereto affixed my signature in the presence of two witnesses.

DANIEL THOMAS WARREN.

Witnesses:

S. T. BLACK,
W. H. RITCHIEY.
